UNITED STATES PATENT OFFICE

WARREN R. WALKER, OF GREAT KILLS, NEW YORK, ASSIGNOR TO GENERAL ELECTRIC
VAPOR LAMP CO., OF HOBOKEN, NEW JERSEY, A CORPORATION OF NEW JERSEY

LIQUID-FLOW SWITCH

Application filed November 25, 1924. Serial No. 752,100.

My present invention relates to switching apparatus, such as employed in electric sign systems, using electric switches of the liquid flow type which are adapted for making and breaking a circuit with a predetermined interval of time between successive makes and breaks and a predetermined interval of time between successive breaks and makes. This application is a continuance in part of my co-pending applications Serial Numbers 722,426 and 734,184, the latter application having been issued February 7, 1928, as Patent No. 1,658,618.

Heretofore in electric systems such as sign flashing systems in which current is alternately cut off from the load for a predetermined length of time and then applied to the load for a predetermined length of time switches of the liquid flow type have been used in some cases, but these switches have required auxiliary apparatus such as dash pots, additional switches, or at least additional contacts therein, for injecting a time lag or interval into one phase of the operation of the switch. It is a purpose of my present invention to provide switching mechanism utilizing a single switch of this type which by virtue of its construction and mounting will inherently operate with a time lag before both the make and the break operations.

A further object of my invention is to provide a suitable electric circuit embodying the switch of my invention and a load which is alternately and for predetermined lengths of time energized and deenergized.

In the drawings forming a part of this application:

Fig. 1 is a longitudinal sectional view in elevation of a switch embodying my invention showing an electrode entering from below into a chimney or cup having an opening therefrom which is intermediate of the top and bottom of the main body of the switch in a closed position thereof and a baffle electrode adapted to control the flow of mercury in the switch both into a circuit making position and into a circuit breaking position.

Fig. 2 is a sectional view along line 2-2 of Fig. 1.

Fig. 3 is a similar diagrammatic view showing the switch of Fig. 1 incorporated in a circuit including a solenoid adapted to operate the switch, said switch being shown in an intermediate position through which it rapidly passes a moment after said solenoid is deenergized. 55

Fig. 4 is a diagrammatic view of the switch of my invention in a sign flash or load circuit comprising the switch operated solenoid connected in series with the switch and load. 60

Fig. 5 is a diagrammatic view of a system similar to that of Fig. 4 but with a solenoid connected in parallel with the load. 65

Fig. 6 is a diagrammatic representation of the switch of Fig. 1 in a closed circuit position. 66

Fig. 7 is companion to Fig. 6 and shows the switch thereof immediately after being 70 tilted into the circuit opening position.

Fig. 8 is a view similar to that of Fig. 7 showing the mercury immediately after circuit has been broken between the part of the main body of mercury and the mercury in the 75 electrode containing cup.

Fig. 9 is a view of the switch in the closed circuit position of Fig. 6 substantially immediately after it has been moved thereinto from the complete open circuit position of 80 Figs. 7 and 8.

Fig. 10 is a variation of the apparatus of Fig. 3.

In the drawings the sealed envelope 1 which is of suitable glass or other vitreous material encloses a body of mercury 2 which in a closed circuit position extends above the upper limits of the cup or chimney 3 formed in said envelope 1 and closed to the outside and to the interior of said envelope 1 except at 85 its top. The electrode 4 sealed into said cup 3 from the outside terminates in said cup below the edge of the opening thereof. Positioned near said cup 3 and extending substantially across the full cross section of the envelope 1 is the baffle electrode 5 which connects with the lead 6 which enters said envelope 1 through a seal at one end thereof and extends longitudinally thereof to said baffle electrode 95 5. At the bottom of said baffle electrode 5 is 100

formed a small opening or notch 7 in the form of a V which serves as a restricted passageway for said mercury 2 from a closed circuit position into an open circuit position thereof and vice versa. At the top of said baffle electrode the opening 8 therethrough allows the passage of gas from one part of the switch to another to equalize the effect of the flow of mercury from one position to another. The baffle electrode 5 extending across the switch chamber divides it into two sub-chambers in one of which, 9, is positioned said cup 3. The size of sub-chamber 9 is determined by the time limits in which the switch can be made to operate in the closed circuit position after it has been tilted therefrom into a corresponding open circuit position, that is, it is determined by the amount of mercury which in said open circuit position can be held in said chamber 9 back of said baffle electrode 5 while said mercury is flowing through said opening 7 to a level below the lower limit of the edge of said cup 3 when the circuit through the switch will of course be disconnected at this point. In predetermining the size of said chamber 9 the height of said cup 3 and the size of openings 7 and 8 must of course be considered. The size of the other sub-chamber 10, is determined by the amount of mercury which it is required to hold in the open circuit position of the switch.

In Fig. 3 is shown the switch of Fig. 1 mounted on a panel 11 which is movable about a pivot 12 near one end thereof. The arm 13 connects the panel 11 to the armature 14 of solenoid 15 through a slotted pivot joint 16. Said switch 1 and solenoid 15 are connected in series to current supply mains 17 and 18. The pivot 12 and armature and solenoid 14 and 15 are positioned with respect to said switch 1 and panel 11 so that said solenoid upon energization through said mains 17 and 18 will actuate said switch to move it into the open circuit position, and so that the weight of said switch 1 and panel 11 will act to move the switch into a closed circuit position.

The solenoid 15 depending upon the load, source of supply, and other operative conditions is connected in circuit either in parallel or in series with said load. In Fig. 4 the solenoid 15 is shown as being connected in series with load 19. In Fig. 5 the solenoid 15 is shown connected in parallel with load 19.

In the operation of the switch of my invention, to secure a delay in the making of the circuit therethrough from the time it is moved into a circuit making position and to secure the delay in the breaking of a circuit therethrough when it is moved into an open circuit position the following phases of operation are gone through.

Referring to Figs. 6, 7, 8 and 9, the switch being in a closed circuit position as in Fig. 6 and the mercury 2 therein forming a continu-

ous body and connecting said electrode 4 to said baffle electrode 5 to secure a delayed opening of the circuit through the switch, it is moved, for example, into the position shown in Fig. 7 in which the main body of mercury 2 held by said baffle 5 and flowing through a restricted opening 7 occupies an appreciable and predetermined period of time in flowing from a position in said sub-chamber 9 at a level above the lower limit of the edge of cup 3 to a level below said lower limit of the edge of cup 3 below which point the mercury is divided into two bodies one of which 2' is within said cup 3 and the other part 2 is without the limits thereof as shown in Fig. 8. The said body 2 will of course attain its equilibrium entirely within said sub-chamber 10. In securing an establishment of current path through the switch at a predetermined interval after the switch is moved from an open circuit position to a closed circuit position the switch is moved from the position with the mercury as shown in Fig. 8 into the position shown in Fig. 9, in which the main body of mercury 2 is banked up in said sub-chamber 10 back of baffle 5 from where it flows through said restricted opening 7 into sub-chamber 9 where upon attaining a level above the lower limit of the edge of said cup 3 and communicating with the mercury 2' in said cup a circuit path is established through the switch, equilibrium of mercury in said position being shown in Fig. 6.

In the operation of the switch in the circuit shown in Figs. 3, 4 and 5 and starting from the open circuit position, the weight of the switch and panel will cause the switch to be moved to the closed position thereof as shown in Fig. 9 in which position the mercury will through a predetermined period of time flow from the circuit breaking position to a circuit making level as indicated in Fig. 6. Upon the establishment of a circuit through the switch energization of solenoid 15 and load 19 by current supplied from mains 17 and 18 takes place. Upon energization of said solenoid 15 the armature 14 is moved, causing the switch and panel to move together through the position shown in Fig. 3, and to come to rest with the switch in the position shown in Fig. 7. In this new position a considerable portion of the mercury in said switch 1 is confined in sub-chamber 9 back of baffle electrode 5, from where it will flow through a predetermined period of time through said restricted opening 7, disconnecting the circuit through the switch when the mercury level falls below the lower limit of the edge of said cup 3, at which time the main body of mercury 2 is disconnected from the body of mercury 2' contained in said cup, as shown in Fig. 8. Upon the opening of the circuit through the switch and the consequent deenergization of the solenoid 15 the

switch through its weight and that of the panel 11 and other parts connected thereto will again move into the circuit closing position whereby a cycle of the switch operation is completed which cycle will continue in this form of my invention as long as current is supplied through mains 17 and 18. As disclosed in my said Patent 1,638,130, the electrodes 3 and 5 will be protected from any 10 arcing which may occur in the making or breaking of circuit through the switch by the mercury bodies 2 and 2', between which said making and breaking occurs. The material of the envelope of the switch 1 will be protected from such arcing by the position away from said envelope of the rim of said cup 3 which rim, as disclosed in said co-pending applications, is itself protected by being made of material which is resistant to temperatures upon such arcing.

The switch envelope is when desired provided with an atmosphere of gas such as hydrogen and nitrogen which serves to quench any such arcing and to conduct heat resulting 25 therefrom rapidly from the interior to the exterior of the switch.

While I have shown and described the baffle 5 as being of metal, it is to be understood that where desired the baffle 5 is made of insulating material such as fused silica, porcelain, hard glass, etc., and mounted on the lead wire 6 in such a way that the said lead wire connects with the mercury on the appropriate side of said baffle 5 essential to the proper 30 functioning of the switch, or said baffle 5 may be mounted on the wall of the container and the lead wire 6 connecting with the mercury in any well known manner.

Furthermore, the described barrier effect 40 obtained with the baffle 5 is obtained in another embodiment, useful in the arts generally, by simply constricting the tube 1, as by drawing out the said tube, at the point where the said barrier or baffle effect is required to 45 cause the necessary restriction of the flow of the mercury in its ascent or descent of the wall of the cup to secure the desired time interval before make and break of the circuit through the switch, the usual gas by-pass for the con-50 striction between the chambers being provided where necessary.

In the embodiment shown in Fig. 3, the armature 14 is of the balanced type and extends through the coil 15 so that when it is 55 energized it moves the switch panel 11 about the pivot 12.

In those cases where minimum energy in the operating solenoid is desirable I prefer to pivot the panel adjacent to the bar 13 and reverse the switch 1 on said panel and mount the solenoid as shown. In this arrangement the moving system is so balanced about the pivot 12 that small amounts only of electrical energy are required to move the armature

14 into the solenoid 15 to operate the switch. Such a device is shown in Fig. 10.

In the operation of this form of my invention when the mercury in the switch reaches the open circuit position as shown in Fig. 10, the solenoid 15 is deenergized and the weight of the switch 1 and panel 11 overbalancing the armature 14 and arm 13 about said pivot 12, the switch and panel will drop whereby the switch attains the closed circuit position as shown in Figs. 9 and 6. The mercury 2 will then during a predetermined length of time flow from the open circuit position into the closed circuit position whereby said solenoid 15 and load 19 are energized. 75 The solenoid 15 being energized armature 14 is pulled down and the switch 1 on its panel 11 will be tilted up into the circuit opening position as indicated in Fig. 7 in which position the mercury will flow from chamber 9 into chamber 10 to thereby break the circuit between electrodes 4 and 6 as indicated in Fig. 8. The circuit then being broken and the solenoid 15 deenergized the weight of the switch 1 and panel 11 will again cause the switch to tip about said pivot 12 into the circuit closing position thereof, in which position the circuit will again be closed by the flowing mercury and the cycle of opening and closing be completed. The alternate 90 opening and closing of the switch in successive cycles in the manner above described will continue as long as leads 17 and 18 are properly energized.

When desired, I employ for moving the switch in the apparatus of Fig. 3 or Fig. 10 as auxiliary to or in place of the weight of the switch or of the switch and its panel 11 a spring 20 or a comparatively heavy weight 21 attached to the switch or its panel 11 for the purpose of overcoming the weight of the armature 14 in the operation of the switch in the movement opposite that caused by the actuation of said armature 14 by said solenoid 15.

I claim:

1. In a switching apparatus, a single circuit time delay switch of the liquid flow type pivoted to fall of its own weight into one of its operating positions, and having means therein for controlling the time interval of the opening and closing of the circuit there-through, a solenoid for moving said switch into the opposite operating position, said solenoid being connected in series with said switch, current supply leads for said switch and solenoid circuit, and a load connected to leads from the switch-solenoid circuit.

2. In a switching apparatus, a single circuit time delay switch of the liquid flow type pivoted to fall of its own weight into one of its operating positions, and having means therein for controlling the time interval of the opening and closing of the circuit there-through, a solenoid for moving said switch

- into the opposite operating position, said solenoid being connected in series with said switch, a current supply for said switch and solenoid, and a load in series with said switch.
- 5 3. In a switching apparatus, a single circuit time delay switch of the liquid flow type pivoted to fall of its own weight into one of its operating positions, and having means therein for controlling the time interval of the opening and closing of the circuit therethrough, a solenoid for moving said switch into the opposite operating position, said solenoid being connected in series with said switch, a current supply for said switch and solenoid circuit, and a load in parallel with said solenoid.
- 10 15

Signed at Hoboken, in the county of Hudson and State of New Jersey, this 24th day of November, A. D. 1924.

20 WARREN R. WALKER.
